Inventor.

Otto Paul Cramer,

By Henry Orth Atty.

UNITED STATES PATENT OFFICE.

OTTO PAUL CRAMER, OF GENEVA, SWITZERLAND.

GAS AND AIR REGULATING DEVICE FOR INCANDESCENT MANTLE BURNERS.

1,418,237.

Specification of Letters Patent. Patented May 30, 1922.

Application filed August 15, 1921. Serial No. 492,436.

To all whom it may concern:

Be it known that I, OTTO PAUL CRAMER, engineer, citizen of Germany, residing in Geneva, Switzerland, and whose post-office address is 118 Rue des Eaux-Vives, have invented certain new and useful Improvements in Gas and Air Regulating Devices for Incandescent Mantle Burners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The principle of regulating the admission of gas in incandescent mantle burners, that is, by the use of an injecting device wherein the regulating socket is movable upon a stationary core provided with a needle, is well known in current practice.

In all dispositions making use of this principle, the said socket is moved upon the core by means of a screw thread in such manner that by screwing or unscrewing the socket, the needle of the fixed core is caused to obstruct to a greater or less degree the aperture provided in the bottom of the socket whereby the flow of gas is made greater or less.

In the disposition according to my invention, the screw thread is omitted, and only a smooth cylindrical surface exists between the socket and the core. The socket is caused to rise or descend with reference to the core carrying the needle by means of a pin which is provided upon the socket, the said pin passing through an oblique slot in the burner tube. By moving the pin in the horizontal direction it is made to follow the inclination of the oblique slot, thus causing the socket to descend vertically and causing it to recede from the needle; thereby affording an increased flow of gas.

For rotating the movable socket of the injector it is preferable to make use of a ring provided with a toothed slot engaging a key provided with a pinion and this toothed slot device is also applicable to effect the vertical or horizontal movement of the ring or the bell-shaped member for regulating the admission of air.

The accompanying drawings which are given by way of example show various embodiments of my invention.

Fig. 1 is a vertical section of a gas injector.

Fig. 2 is a front view of the same, with the injector proper indicated by dotted lines. 60

Figs. 3 and 4 show a modified form of the device in vertical and horizontal section.

Figs. 5 and 6 show another modified form of the device.

Fig. 7 is an elevation of a gas burner tube 65 wherein the adjustment of the air admission as well as the gas admission is effected by means of toothed grooves.

Fig. 8 is a separate view of the ring used for gas adjustment. 70

Fig. 9 is a separate view of the bell-shaped member used for the admission of air.

Fig. 10 is a plan view showing the method of construction of the said bell shaped member. 75

Figs. 11 and 12 show two modified forms of the device for admission of air.

Referring to the construction of the injector shown in Figs. 1 and 2, the fixed core 1 carrying the needle 2 is constituted by a 80 smooth cylindrical portion 3 upon which the movable socket 4 may be moved vertically, the latter being provided with a stuffing box 5 whose packing 6 is pressed upon the smooth portion 3 of the fixed core 1. The 85 movable socket 4 may be moved by means of a pin or handle 7 extending through an oblique slot 8 in the fixed tube 9 of the burner. This movement may be effected either in a direct manner by the pin 7 if 90 the latter is given the form of a handle, or by means of a ring provided with a rack, as will be hereafter set forth.

In the modified form shown in Fig. 3, the device has the same character, but it also 95 comprises a recess 10 for retaining the impurities which may be contained in the gas and are susceptible of obstructing the orifice of the movable socket. In this case, the gas passes through the apertures 11 in order to 100 reach the cut out portion 12 of the fixed core 1. The concentric disposition of the gas jet is obtained by providing the lower part of the fixed core 1 with a guide flange 13 which is cut off at both sides at 14 (Fig. 4) to 105 afford a passage for the gas.

Instead of disposing the said recess for receiving impurities in the lower part of the core 1, this recess 10^a may be disposed at the admission end of the connecting member, as 110 shown in Figs. 5 and 6, and in order to cause the impurities to fall into the recess and to

provide a free passage for the gas, the recess is covered by a small square member formed of corrugated sheet metal. Instead of rotating the movable socket 4 by means of a handle 7 which is movable within a slot 8 formed in the burner tube, Fig. 2, this movement may be carried out by means of a ring 16 having a slot 17 provided with teeth 17^a, Figs. 7 and 8, which is mounted upon the burner tube 9.

The ring 16 is provided with a second vertical aperture 18 wherein passes a screw 7^a secured to the movable socket of the injecting device whereby the latter shall be actuated upon moving the ring 16 by means of a key with milled head 19 having one portion in the form of a toothed pinion at 20 engaging the rack 17^a of the ring 16.

In order to prevent dust from being drawn into the air apertures, the usual type of ring is replaced by a bell shaped member 21, Figs. 7 and 10; provided in the interior with four vanes 22 which are cut out flatwise in the bottom of the bell shaped member (Fig. 10) and then curved inwardly in order to more or less close the usual apertures formed in the tube 9 of the burner. Adjacent the bottom of the bell-shaped member 21 is formed a rectangular aperture 17^b, Figs. 7 and 9, having one side thereof 17^c toothed to constitute a rack engaging the pinion 20^a forming part of the stem 19^a.

Instead of applying the arrangement to a bell-shaped member, the same may be applied to effect the movement of a ring of the usual type provided with apertures 23 (Fig. 11) and having formed therein the aperture 17^b with the tooth portion 17^c.

If the adjustment is to be obtained by the vertical movement of a ring 23^a upon an aperture 24 formed in the burner tube, Fig. 12, the cut out portion 17^b with the teeth 17^c is disposed vertically upon the said ring.

The use of the present gearing device will provide for an exact control of the rotation, and the adjustment is thereby of a more precise character. The apparatus possesses a great advantage from the fact that it is not susceptible of being accidentally put out of order while being cleaned, dusted or the like.

Having now particularly described and ascertained the nature of my said invention and in what manner the same is to be performed, I declare that what I claim is:—

1. A gas and air regulating device for incandescent mantle burners, comprising a burner tube, a cylindrical injector core mounted in the tube and having a smooth periphery and a regulating needle, a regulating socket surrounding the core and having screw-threads formed on its outer periphery, a nut mounted on said threads and having a flanged end, a packing compressed between said flanged end and the end of the socket engaging the periphery of the core

and forming a gas-tight connection with the latter, and a pin on the socket engaging an inclined slot in the burner tube.

2. A gas and air regulating device for incandescent mantle burners, comprising a stationary injector core with regulating needle, a regulating socket without screw thread which is vertically movable upon the stationary core, a stuffing box with packing clamping the smooth portion of the stationary core, an inclined slot in the burner tube, a pin engaged in the said inclined slot and in a vertical slot, a revoluble ring having a vertical slot formed therein, a horizontal slot provided with rack teeth formed in the said revoluble ring, a pinion with actuating stem for rotating the ring and consequently the movable socket of the injector, an air regulating bell shaped member disposed below the said injector, vanes which are cut out of the end portion of the said bell shaped member and are adapted to cover the air admission orifices, a groove provided with rack teeth formed in the bell shaped member, and a pinion with actuating stem for rotating the said bell shaped member.

3. A gas and air regulating device for incandescent mantle burners, comprising a stationary injector core having a regulating needle, a vertically movable regulating socket surrounding the core, a stuffing box on the socket having a packing engaging the core, a burner tube having an inclined slot, a pin engaging the slot, a recess for receiving impurities disposed at the lower part of the movable socket, a guide flange disposed at the base of the core, and an air regulating bell-shaped member disposed below the injector.

4. A gas and air regulating device for incandescent mantle burners, comprising a stationary injector core with regulating needle, a vertically movable regulating socket surrounding the core, a stuffing box on the socket having a packing engaging the core, a burner tube having an inclined slot, a pin engaging the slot, a recess for receiving impurities disposed at the upper part of the stationary core, a corrugated metal plate adapted to conduct the impurities into the recess, and an air regulating bell-shaped member disposed below the injector.

5. A gas and air regulating device for incandescent mantle burners, comprising a stationary injector core having a regulating needle, a vertically movable regulating socket surrounding the core, a stuffing box on the socket having a packing engaging the core, a burner tube having an inclined slot, a pin engaging the slot, a rotatable ring having rack teeth for controlling the injector socket, a pinion having an actuating stem engaging the rack teeth for rotating the ring, a rotatable air regulating ring provided with a groove having rack teeth formed therein,

and a pinion provided with a stem for controlling the air regulating ring.

6. A gas and air regulating device for incandescent mantle burners, comprising a stationary injector core having a regulating needle, a vertically movable regulating socket surrounding the core, a stuffing box on the socket having a packing engaging the core, a burner tube having an inclined slot, a pin engaging said slot, a rotatable

ring having rack teeth for controlling the injector socket, a pinion having an actuating stem for rotating the ring, a vertically movable air regulating ring, a groove having rack teeth formed in the latter, and a 15 pinion having a stem for controlling said vertically movable ring.

In testimony that I claim the foregoing as my invention I have signed my name.

OTTO PAUL CRAMER.
